UNITED STATES PATENT OFFICE.

THOMAS Z. MAGARRELL, OF CHICAGO, ILLINOIS, ASSIGNOR TO ANDREW P. W. SKINNER, OF SAME PLACE.

LAMP LIGHTER AND EXTINGUISHER.

SPECIFICATION forming part of Letters Patent No. 259,645, dated June 13, 1882.

Application filed March 31, 1882. (No model.)

To all whom it may concern:

Be it known that I, THOMAS Z. MAGARRELL, of Chicago, Cook county, Illinois, have invented certain new and useful Improvements 5 in an Apparatus for Lighting and Extinguishing Lights, of which the following is a description that will enable others to make and use the same, reference being had to the accompanying drawings, and to the letters of reference marked thereon, forming a part of this 10 specification.

The object of this invention is to provide a device for lighting and extinguishing lamps without the necessity of removing the chimneys at each operation, and it is also adapted to 15 be used in connection with gas apparatus; and it consists of a tubular handle or staff, the lower end of which is provided with a mouth-piece, while the upper end is bent around and 20 contracted so as to detachably engage with a tubular extension holding a wick and lighting-fluid, as will be hereinafter more fully set forth.

Figure 1 is an elevation of a device embodying my improvement; Fig. 2, a longitudinal 25 section of the tubular handle, and Fig. 3 a longitudinal section of the wick-tube and connecting part.

Referring to the drawings, A represents the tubular handle or staff, which may be of any 30 desired length, the lower end of which is enlarged to provide the mouth-piece a, while the upper end is gradually contracted, so as to detachably engage with the extension a' of the wick-tube B, forming a telescopic joint, as 35 shown in Fig. 1 of the drawings. The upper end of the handle A is provided with the wrench a², which is of the proper shape to engage with the thumb-screw of gas-fixtures for turning on and off the light.

40 The wick-tube B incloses the wick a³, one

end of which projects from the end of the tube, and at which point it is lighted when required for use. The lighting-fluid is supplied to the wick-tube by removing the stopple a⁴. The lateral tubular extension a' connects the wick-tube with the handle A. The wick-tube, as shown in Fig. 1 of the drawings, is properly arranged to pass down in the inside of a chimney and light the lamp without removing the chimney; or it may be rotated so as to project upward, 45 50 as represented by the dotted lines, to light the gas.

When using the device as an extinguisher the wick-tube should be removed and the contracted end of the handle A inserted in the 55 lamp-chimney, the light being extinguished by the operator placing his mouth to the opposite end of the tubular handle and blowing through the same. By this arrangement a device is provided whereby the many lamps of 60 a chandelier may be lighted without having to remove the chimneys, which is not only convenient, but also economical, as it causes a great saving in the breakage of lamps and 65 chimneys.

This device may be constructed of any material suitable for the purpose and at a reasonable cost.

Having thus described my invention, what I 70 claim as new, and desire to secure by Letters Patent, is—

The combination, with the tubular handle A, of the wick-tube B and the tubular extension a', substantially as and for the purpose set forth.

THOMAS Z. MAGARRELL.
